UNITED STATES PATENT OFFICE.

HENRY F. SCHMIDT, OF PITTSBURGH, PENNSYLVANIA, ASSIGNOR TO WESTINGHOUSE ELECTRIC & MANUFACTURING COMPANY, A CORPORATION OF PENNSYLVANIA.

FLUID-TRANSLATING DEVICE.

1,262,102.

Specification of Letters Patent. Patented Apr. 9, 1918.

Application filed September 14, 1914. Serial No. 861,636.

To all whom it may concern:

Be it known that I, HENRY F. SCHMIDT, a citizen of the United States, and a resident of Pittsburgh, in the county of Allegheny and State of Pennsylvania, have made a new and useful Invention in Fluid-Translating Devices, of which the following is a specification.

This invention relates to fluid translating devices, such, for example, as ejectors, in which the kinetic or velocity energy of the motive fluid is employed in exhausting fluid from a receptacle to be evacuated, or in compressing a fluid from a region of lower to a region of higher pressure.

In ejectors employing diffusers for building up pressure by converting kinetic into potential or pressure energy, pulsations in the medium traversing the diffuser occur for various reasons. If these pulsations are of sufficient magnitude that the loss occasioned by shock results in a sufficient diminution of the velocity of the medium, and consequently of the available kinetic energy, so that the energy is reduced below that necessary to overcome the external or discharge pressure, the velocity in the diffuser will instantly fall to zero. This will reduce the expelling force to zero and consequently occasion a flow in the reverse direction or from the outlet of the diffuser back into the region of lower pressure.

An object of this invention is, therefore, to produce an ejector in which means are employed for preventing pressure oscillations in the diffuser from becoming large enough to detrimentally affect the operation of the ejector.

A further object of the invention is to produce a fluid translating device, of the kinetic type, in which means are employed for maintaining the operation of the device substantially constant for practically all varying conditions.

A still further object is to produce a fluid translating device employing the kinetic or velocity energy, of the motive fluid delivered to it, in transferring fluid from a region of lower to a region of higher pressure, which automatically adjusts itself to variations in the quantity of fluid conveyed, thus preventing fluctuations of pressure in either the region of higher or lower pressure.

These and other objects, which will be

made apparent to those skilled in the art throughout the further description of the invention, are attained by apparatus embodying the features herein described and illustrated in the drawing accompanying 60 and forming a part of this application.

In the single sheet drawing I have shown, more or less diagrammatically, a sectional view of an ejector embodying my invention.

The ejector illustrated comprises a combining or suction chamber 9, which is provided with an inlet port 2, nozzles 4 for discharging fluid from a source of fluid pressure through the combining or suction 70 chamber 9 into a diffuser 3, through which the combined media discharged from the combining chamber 9 are discharged from the lower to the higher pressure through the outlet 7 of the diffuser 3.

The diffuser 3 has fitted near its outlet one or more well rounded conical nozzles 8 pointing in the direction of normal flow of the media through the diffuser 3. This nozzle, or nozzles, is provided so as to permit 80 the passage of fluid only through the opening and not around the edges of the diffuser. The cross-sectional area of the diffuser 3 is so designed that substantially all the kinetic energy in the fluid entering the diffuser is transformed into the work of translation before reaching the first of the nozzles 8.

The nozzles 8 are so contracted that there is a slight drop of pressure through them 90 to the discharge of the diffuser 7. Thus the diffuser 3 will compress or move the medium discharged from the nozzles 4 and entrained in the chamber 9 against a pressure slightly higher than at the outlet of the diffuser 7.

It is a well known law of hydraulics and thermodynamics that the coefficient of flow through a well rounded orifice is essentially unity, and also that the coefficient of flow through an open ended tube projecting into 100 the medium discharging into it is approximately 47/100 of the flow through a well rounded orifice. The result is that with an arrangement of the nozzle or nozzles 8 such as disclosed, the flow in the normal direction will occur with approximately only one-half the drop of pressure through the nozzle or nozzles 8 as is required to cause a flow in the opposite direction.

It is well known that harmonic oscilla-

tions, such as the shock vibrations set up in fluids under certain conditions, can only be propagated or increased in magnitude through resonance so long as the resistance 5 which is overcome by the wave formation is equal in both directions longitudinally of the wave motion. It will be evident, therefore, that in the arrangement shown, resonance is prevented, and shock vibrations 10 tending to be set up, due to the passing of a quantity of medium, other than for which the diffuser was designed, will be prevented from attaining a magnitude sufficient to cause a great enough loss of kinetic energy 15 that breaking down will occur. By breaking down I mean an equalization of the pressures at the outlet 7 and in the chamber 9, or momentary fluctuations of pressure in the diffuser occasioned by conditions other than 20 variations in the delivery of fluid by the nozzles 4 or variations in the amount of medium entering the chamber 9.

While I have illustrated but one embodiment of my invention, it will be apparent to 25 these skilled in the art, that the drawing is merely illustrative, and that various changes, modifications, substitutions, additions and omissions may be made in the apparatus illustrated without departing from the spirit 30 and scope of my invention as set forth by the appended claims.

What I claim is:

1. In an ejector, a suction chamber, a diffuser communicating therewith, a nozzle for 35 delivering expelling medium through the diffuser, and a plurality of converging nozzles of progressively increasing area located at the discharge end of the effective portion of the diffuser, pointing in the direction 40 of flow through the diffuser and passing all of the fluid issuing from the diffuser.

2. In an ejecting device, a chamber to which medium to be expelled is delivered, a diffuser communicating therewith, and 45 through which the medium is expelled, a nozzle for delivering expelling medium through the diffuser, and a converging nozzle extending across the outlet of the effective portion of the diffuser, converging in 50 the direction of the normal flow of medium, and passing all the fluid issuing from the diffuser.

3. In an ejecting device, a chamber to which fluid to be expelled is delivered, a diffuser communicating therewith, and 55 through which the fluid is expelled, means for delivering a stream of expelling fluid through said diffuser, and a well rounded nozzle, located at the end of the effective 60 portion of the diffuser, pointing in the direction of flow through the diffuser, and passing all of the fluid issuing from the diffuser.

4. In an ejecting device, a chamber to which medium to be expelled is delivered, a diffuser communicating therewith, and 65 through which the medium is expelled, means for delivering a stream of expelling medium through said diffuser, and a well rounded nozzle pointed in the direction of 70 normal flow through diffuser, located at the outlet of the effective portion of the diffuser.

5. In an ejecting device, a chamber to which fluid to be expelled is delivered, a diffuser communicating therewith, and 75 through which fluid is expelled, means for delivering a stream of expelling fluid through said diffuser and a well rounded converging nozzle located at the outlet of the effective portion of the diffuser and offering a greater resistance to flow in a direction opposite to the normal flow than in 80 the direction of the normal flow through the ejector.

6. In combination with an ejector, means 85 located at the outlet of the effective portion of the diffuser for preventing upsetting, comprising well rounded nozzles of successively increasing area and with their outlets pointing in the direction of flow through the 90 diffuser.

7. In an apparatus of the character described, a chamber from which medium is to be exhausted, a diffuser communicating therewith, and through which medium is 95 expelled, means for delivering expelling fluid through the diffuser, and means located within the diffuser for dampening harmonic waves propagated in the diffuser.

8. In an apparatus of the character described, a chamber from which medium is to be exhausted, a diffuser communicating therewith, and through which medium is 100 expelled, means for discharging an expelling medium through said diffuser, and 105 means comprising a plurality of converging nozzles located at the discharge end of the effective portion of the diffuser and of successively increasing area.

9. In an apparatus of the character described, a chamber from which medium is to be exhausted, having a medium inlet and a medium outlet port, means for discharging expelling fluid through the outlet port of said chamber, a diffuser communicating 110 with the outlet port and a plurality of valveless orifices intercepting the diffuser and offering a greater resistance to flow in one direction than in the other.

In testimony whereof, I have hereunto 115 subscribed my name this 21st day of August, 1914.

HENRY F. SCHMIDT.
